UNITED STATES PATENT OFFICE.

CHARLES H. KESTENMAN, OF PROVIDENCE, RHODE ISLAND, ASSIGNOR TO KESTENMAN BROS. MFG. CO., OF PROVIDENCE, RHODE ISLAND, A CORPORATION OF RHODE ISLAND.

EXPANSIBLE BAND, CHAIN, OR THE LIKE.

Application filed June 9, 1925. Serial No. 35,936.

This invention relates to improvements in expandable metal bands, chains, or linkages for use in the manufacture of bracelets, necklaces, girdles, or other articles of jew-
elry and the like.

A principal object of the invention is to provide an improved article of manufacture of the type specified having closely associated articulated links or chain-elements 10 which are adapted to flex, one in relation to the other, and to move longitudinally relatively to each other to allow expansion in the length of the bracelet, necklace, girdle, or other article in which it is incorporated.

One object of the present improvement is to provide an expandible band or chain having ornamental pierced links or telescoping elements which are so constructed and combined that the piercings or openings register 20 without obstructing the open effect when the links are in closed relation.

Another object of the improvement is to provide a device of the type specified having resilient expansion means contained 25 within the links to normally maintain them in contracted relation, said resilient means being protected and hidden from view by the enclosing links.

Another object of the improvement is to 30 provide a device of the type specified which may be manufactured from sheet-metal blanks struck up in dies and assembled with a minimum of hand operations.

Another object of the improvement is to 35 provide a device of the type specified having a neater and more ornamental appearance and of stronger construction and less liable to be broken or damaged in use than other similar devices.

Further objects of the improvement are 40 set forth in the following specification which describes several preferred embodiments of the invention as illustrated in the accompanying drawings. In the drawings:

Fig. 1 is a perspective view illustrating 45 the general appearance of the band or chain and showing it with the links in contracted relation, but flexed in substantially circular form;

Fig. 2 is an enlarged bottom plan view 50 showing several of the connected links and illustrating two of the outer main links in section to disclose the resilient expansion means enclosed therein;

Fig. 3 is a side view of several of the links

with two of the outer links illustrated in section on the line 3—3 of Fig. 2;

Fig. 4 is a cross-sectional view taken on the line 4—4 of Fig. 2, showing the sliding arrangement between the outer main links 60 and the inner connecting links;

Fig. 5 is a perspective view showing the under side of several of the assembled links and illustrating the manner in which the inner sliding link is drawn out to be hooked 65 into connection with the next adjacent main link;

Fig. 6 is a perspective view of the outer or main link;

Fig. 7 is a perspective view of the sheet- 70 metal blank from which the inner sliding link is constructed;

Fig. 8 illustrates the blank after it is bent or formed into the inner link or slide;

Fig. 9 is a view showing a modification 75 in the form of the blank for the inner link or slide;

Fig. 10 is a view illustrating the inner link or slide formed from this type of blank;

Fig. 11 is a perspective view of the outer 80 link adapted for use with the slide illustrated in Fig. 10;

Fig. 12 shows a still further modified form of the inner link or slide; and

Fig. 13 is a view of the outer main link 85 employed with the form of slide illustrated in Fig. 12.

My improved band, chain, or linkage consists in general of a series of main elements or outer link-members 2 of box-like form, 90 and relatively flat inner connecting links or slides 3 which normally telescope within the main links but are adapted to be drawn out or extended in relation thereto to provide for the extension of the band or chain as a 95 whole. The main links 2 are open at the center along their under sides and the inner connecting links or slides 3 abut the under side of the top portions of the main links and are provided with lateral wings or 100 flanges which cooperate with the lateral sides of the main links to form housings for the compression springs which hold the links in telescoped relation.

Referring particularly to Figs. 4 and 6, the outer main links 2 are constructed from sheet-metal, with relatively flat top portions 4 which are pierced with openings 5 to add to the ornamental appearance of the article in which the links are employed. Bent at 110

right angles to the top portion 4 of the link 2 are the lateral sides 6 which are folded over again to form bottom flanges 7 extending longitudinally of the link, see Fig. 4 5 which illustrates the main link in section in inverted position or bottom side up. Bent up from the bottom flanges 7 at one end of the main link 2 are ears 9 which partly close the ends of the link except for narrow slots 10 10 under the top portion 4 thereof. At the opposite end of the main link 2 the bent ears 9 are joined by a cross-bar 11, see Fig. 5, which is adapted to receive a hook on the end of the inner link or slide to be next 15 described.

Fig. 7 illustrates the sheet-metal blank from which the inner connecting link or slide 3, shown in Fig. 8, is constructed. The blank 15 consists of a rectangular strip 16 having a narrowed tab 17 projecting from one end which is adapted to be bent around to form a hook 18, as shown in Fig. 8. The blank 15 is cut or sheared, as illustrated in Fig. 7, to form two narrow strips 19 which are bent at right angles to the main strip at points indicated by the dotted lines to form perpendicular flanges, as shown in Fig. 8. These flanges 19 extend longitudinally of the link or slide 3 at a slight distance from the lateral edges thereof, and when the slide is telescoped within the main link 2, as shown in Fig. 4, the flanges 19 cooperate with the bottom flanges 7 and sides 6 of the main link to form trough-like enclosures or housings for a pair of helical springs 20. Bent over from the end of the inner link or slide 3 is a flange 21 against which the ends of the springs 20 bear as illustrated in Figs. 2 and 3, the opposite ends of the springs being held by the upturned ears 9 at the ends of the main link 2. It will be noted by reference to Figs. 7 and 8 that the sheared strips or flanges 19 which are bent at right angles to the main portion of the slide 3 leave a longitudinal bar 22 in the form of a rib or brace extending from one end of the slide to the other. It is also to be noted that the strips 19 are sheared or cut away from the blank in such contour as to form notches 24 in their edges disposed centrally of their length, the purpose of which will later appear.

It is to be further observed that when the inner link or slide 3 is telescoped within the main link 2, as shown in Fig. 2, the longitudinal openings 23 in the slide 3, formed by shearing away and bending over the flanges 19, register with the pierced openings 5 in the top of the enclosing link 2. On the other hand, the central longitudinal strip or bar 22 will underlie the unpierced portion of the top of the link 2 so as not to be visible through the piercings 5. Through this construction and arrangement the assembled links are rendered pervious from top to bot-

tom so as not to obstruct or mar the symmetry of the design of the piercings.

To construct the band or chain from its units as above described the individual inner links or slides 3 are assembled with their enclosing main links 2 by entering them thereinto before the bottom flanges 7 are bent over into place; the springs 20 being also inserted in their housings at the sides of the main links before the end ears or tabs 9 are bent over. Each pair of links assembled in this manner is joined to the next pair by inserting the hook 18 on the inner link into the slot in the end of the next adjacent main link to hook it around the cross-bar 11. To engage the hook 18 on the slide 3 with the cross-bar 11 on the main link 2 the slide is withdrawn from the end of its enclosing link, and in performing this operation the finger nail is inserted in the notches 24 on the edges of the wings 19 to hold it in extended position. With the slide withdrawn and held in this manner the two sections of the chain are carried into angular relation, somewhat as illustrated in Fig. 5, and the hook 18 inserted into the end of the next adjacent main link 2 and hooked around the cross-bar 11. When the several links are connected in this manner the inner links or slides 3 will normally be telescoped within the outer main links 2 under the tension of the compression springs 20. When the links are in contracted relation, as shown at the left in Fig. 2, the outer main links will be held with their ends closely abutting and usually the ends are beveled or inclined inwardly from the top; that is, the sides of the links are of substantially wedge-shape as shown in Figs. 1 and 3, so that the band may be bent into circular form without leaving gaps or open joints between the links. To expand the band or chain along its length the main links may be pulled apart, as illustrated in Figs. 2 and 3, the inner connecting links or slides 3 sliding within the outer links 2 to compress the springs 20 as illustrated at the right in Figs. 2 and 3.

Figs. 9 and 10 illustrate a modification in the shape of the blank and in the construction of the inner link or slide formed therefrom. In this modification of the invention the blank 25 is punched or perforated to form a rectangular opening 26 at its center and the side wings or flanges 27 are sheared away and bent up from its marginal portions at either side of the opening as shown in Fig. 10. With this arrangement of the inner link or slide the perforations or openings 28 in the main link 29 are set closer together as illustrated in Fig. 11 so as to be included within the borders of the rectangular opening 26 in the slide to make the link entirely pervious. 125 115

In Fig. 12 I have illustrated a still fur- 130

ther modification of the inner link 30 as being folded or bent to form vertical flanges 31 without shearing the blank from which the slide is constructed. That is to say, a 5 single flat strip of metal is folded to form an upstanding trough-like portion or box 32 extending longitudinally of its center with side wings 33 which abut and slide on the bottom flanges 7 of the main link 34. With 10 this construction of the slide the tabs or ears 35 are bent up from the side wings 33 to take the thrust of the springs in the main link. The trough-like portion 32 of the slide is pierced or cut away along the center 15 at 36 so as not to show through the perforations 37 in the top of the main link 34, these perforations being arranged closer together as shown in Fig. 13. In this form of 20 the device the end tabs or ears 9 on the main link are bent down from its top instead of being formed as part of the bottom flanges 7. With the modified forms of the inner link or slide as last described the parts are assembled in the continuous band or chain in 25 substantially the same manner as first explained.

It will be observed that my invention provides a particularly simple structure for the band or chain, adapted to give a highly ornamental appearance to the bracelet, necklace, girdle or other article in which it is incorporated, while also rendering the same economical to manufacture, and strong and durable in use. The piercing of the main 30 links enhances the artistic and ornamental appearance of the article, and the arrangement whereby the openings in the top of the main links register with those of the inner links obviates any distortion or obscuring 35 of the design, while giving a particularly delicate and graceful effect to the whole. Moreover, the structural features of the band or chain are entirely hidden from view to avoid a mechanical appearance whereby to heighten the artistic effect.

Various modifications other than those herein shown may be made in the structure and arrangement of the parts of the device without departing from the spirit or scope 50 of the invention. Therefore, without limiting myself in this respect, I claim:

1. In a flexible band or chain, the combination of outer box-like main links having sides bent down from the top and flanges 55 folded inwardly at the bottom thereof to form trough-like portions with ears closing the troughs at their ends, slides slidable within the main links and provided with vertical flanges spaced inwardly from their 60 sides and extending between the bottom flanges and top of the main links to form tubular housings, and springs enclosed in said housings and acting between the

main links and the slides to normally hold the parts in telescoped relation. 65

2. In a flexible band or chain, the combination of a part-tubular main link having an opening extending longitudinally of its under side and bottom flanges at either side of said opening, a relatively flat slide 70 slidable in the main link and provided with flanges bent at right angles thereto and spaced inwardly from its sides to close the space between the edges of the bottom flanges and the top of the main link to provide tubular housings, and springs enclosed in said housings between the flanges on the slide and the sides of the main link and acting between the slide and the main link to hold the parts normally in telescoped relation. 75

3. In a flexible band or chain, the combination of a relatively flat part-tubular main link having a top, sides and bottom flanges extending inwardly at right angles to the 80 side with ears at their ends partly bridging the space between the bottom flanges and the top of the link, a slide slidable in the main link and provided with longitudinal flanges spaced inwardly from its sides to bridge the 85 space between the top of the main link and the edges of its bottom flanges, means at the end of the slide adapted to engage with the end of an adjacent main link, and springs arranged between the flanges on the slide 90 and the sides of the main link and acting between the slide and the main link to normally hold the parts in telescoped relation while allowing expansion of the chain as a 95 whole. 100

4. In a flexible band or chain, the combination of a box-like main link having a relatively flat top, sides bent at right angles thereto and bottom flanges folded inwardly from the sides with ears bent across 105 the openings between the top of the links and its bottom flanges at either end thereof, and one end provided with a cross-bar extending laterally between said ears, and a relatively flat slide slidable in the main link 110 and having portions sheared therefrom and bent at right angles thereto to form flanges spaced inwardly from its lateral edges and cooperating with the top, sides and bottom flanges of the main link to form housings, said slide formed with a hook at one end adapted to hook around the cross-bar at the end of an adjacent main link, and springs enclosed within the housings and acting between the slide and the main link to 115 normally maintain the parts in telescoped relation while adapting them to be extended to allow expansion of the band or bracelet as a whole. 120

In testimony whereof I affix my signature.
CHARLES H. KESTENMAN.
